UNITED STATES PATENT OFFICE.

CHARLES JAFFRYS FORRESTER, OF MANCHESTER, ENGLAND.

VENTILATOR FOR CARRIAGES AND SHIPS.

1,181,866.

Specification of Letters Patent.

Patented May 2, 1916.

Application filed June 27, 1913. Serial No. 776,122

To all whom it may concern:

Be it known that I, CHARLES JAFFRYS FORRESTER, a subject of the King of Great Britain and Ireland, residing at 46 Woodland road, Gorton, Manchester, county of Lancaster, England, fitter, have invented Improvements in Ventilators for Carriages and Ships, of which the following is a specification.

10 This invention relates to ventilators for railway and other carriages, tramcars and ships.

The invention has special reference to ventilators of the kind wherein a current of 15 air passing through an air tube creates an up-draft or suction through a suction or ventilating pipe having a bent or curved end located in said tube and opening toward the exit thereof.

20 The object of the invention is to adapt such a ventilator to railway and other carriages, tramcars and ships and the like which move to and fro, or forward and backward, without being themselves reversed or turned around.

25 In the accompanying drawings:—Figure 1, is a sectional elevation of one embodiment of the invention; and Figs. 2 and 3 are, respectively, an elevation and a sectional plan of a modification.

In the drawing and the following description similar letters of reference indicate like parts.

Referring to Fig. 1, *a* is an air tube having an inlet end *a'* and a downwardly turned exit end *a''*. Within the air tube *a* is located the bent or curved end *b'* of a suction or ventilating tube *b*, said end *b'* opening toward the exit end *a''* of the tube *a*. The 35 suction or ventilating pipe *b*, of course, extends into the vehicle or ship and is led to the required part thereof. The inlet end *a'* of the air tube *a* is provided with an enlargement *h* in which is fitted a smaller inlet *c*, so that a space *j* results between the same and the enlargement *h*. To the space *j* the oppositely disposed inlet *d* is connected by a curved pipe *k*. By this arrangement

of duplex inlets, air entering either of the inlets *c* and *d* is, without the use of a valve 50 or the like, prevented from escaping through the other, and passes through the pipe *a* and escapes at the exit *a''* thereof, the passage of said air creating an up-draft or suction in the suction or ventilating pipe *b*, whereby 55 the vitiated or impure air in the carriage, cabin, or the like, to which the ventilator is fitted, is exhausted through the pipe *b* and passes with said air to the exit *a''*.

In applying the duplex air inlets to a ventilator in which the air tube *a* is divided by a partition *f* into two portions *g*, *g'*, each of which has a downwardly bent exit *a''* and is fitted with a suction or ventilating pipe *b* as shown in Figs. 2 and 3, I provide said 65 portions *g*, *g'* with passages *m*, *m'*, and to each of said passages I fit duplex inlets *c* and *d* arranged as above described in reference to Fig. 1. By this means each of the suction or ventilating pipes *b* is rendered 70 double-acting, and has an up-draft or suction created through it in each direction of motion.

I claim:—

The combination, in a ventilator, of a 75 horizontally arranged air tube having an exit at one end at an angle to the length thereof, a suction pipe extending into the tube and having its end within the tube extending toward the exit, an enlarged air 80 inlet passage at the end of the tube opposite the exit, a reversely disposed inlet pipe communicating with said inlet passage, and a straight inlet tube extending through the 85 passage and having an end less in diameter than the air tube, so that a suction will be created in the suction pipe when air passes through either inlet.

In testimony whereof, I have signed my name to this specification, in the presence 90 of two subscribing witnesses.

CHARLES JAFFRYS FORRESTER.
